UNITED STATES PATENT OFFICE.

FRED N. MIZER, OF ELYRIA, OHIO, ASSIGNOR TO THE GARFORD MANUFACTURING COMPANY, OF ELYRIA, OHIO, A CORPORATION OF OHIO.

ARMATURE FOR DYNAMO-ELECTRIC MACHINES.

1,270,967.

Specification of Letters Patent.

Patented July 2, 1918.

Application filed November 8, 1916. Serial No. 130,116.

To all whom it may concern:

Be it known that I, FRED N. MIZER, a citizen of the United States, residing at Elyria, in the county of Lorain and State of Ohio, 5 have invented certain new and useful Improvements in Armatures for Dynamo-Electric Machines; and I do hereby declare the following to be a full, clear, and exact description of the invention, such as will enable others skilled in the art to which it 10 appertains to make and use the same.

My invention relates to improvements in armatures for dynamo-electric machines, and more particularly to armatures which 15 are to be rotated at a high angular velocity, such for example, as are employed in certain types of electric automobile horns and the like. In the particular use which I have mentioned and also many other uses, the 20 armatures of dynamo-electric machines are subjected to constant jarring and shaking, which tends to loosen or dislodge parts of the built up armature. Sometimes, as in automobile horns, this jarring and shaking 25 takes place at the same time that the armature is rotated at high velocities, exaggerating the tendency to loosen and dislodge the parts. For example, in the use which I have 30 mentioned—that of electric automobile horns, these forces are all acting at the same time to disarrange the construction of the armature.

One of the objects of my invention is to provide an armature which will serve where 35 high velocity is employed, where the armature is jarred or shaken in use, or where all these agencies are at work, to perform the armature functions without the armature parts being disarranged or torn apart. This 40 and other objects of my invention, as well as the invention itself will be better understood from a description of an embodiment of my invention.

Figure 1 is an armature of a dynamo- 45 electric machine showing an embodiment of my invention in elevation, with a portion of the binding cord cut away.

Fig. 2 is a longitudinal section through 50 a part of one end of the armature of the embodiment shown in Fig. 1.

Fig. 3 is an end view of the portion of the

embodiment of my invention shown in Fig. 2.

Fig. 4 is a detail view of an element employed in the embodiments shown in Figs. 55 1, 2 and 3.

Referring now to the drawing and to the embodiment of my invention shown therein, at 5 is shown the armature shaft which here consists of a shaft proper 6 and a sleeve 60 7 thereon. For convenience of manufacture the particular embodiment illustrated is made in the manner shown, though it will be obvious to those skilled in the art that the parts 6 and 7 may be one. At 8 is shown the 65 armature and at 9 are shown armature windings which terminate at 10. The section 7 of the armature is provided with commutator recesses 11. In the embodiment shown the end walls 12 of these recesses are tumbled or drawn in, as shown at 13, so that the 70 opening 14 thereof is restricted at the top and smaller than at the bottom 15. The recess is lined with insulating material 16, which in general follows the contour of the 75 walls of the recess. The commutator segments are shown at 17 and fit within the recess, the insulating lining being interposed between the walls of the recess and the commutator segments. 80

At 20, 20 are shown circuit connectors provided with relatively short limbs 21 which extend under the commutator segment 17. The commutator segments are provided with recesses 23 for the reception 85 of the limbs 21. The connectors 20, 20 are provided with relatively long limbs 22 which extend along the end of the commutator slots between the ends of the commutator segments and the insulating material 90 and are folded over the armature shaft, as shown in Fig. 1, fitting tightly thereagainst. A cushioning material, such as a plurality of cords 25 may be employed between the 95 armature shaft and the limbs 22 of the connectors 20, 20. The end 10 of the armature winding is connected, as shown at 30, to the limb 22 of the connector 20 and these parts are bound tightly to the armature shaft by suitable means, such as by threads 31 wound around the armature shaft over the ends 10 100 of the armature windings and the limbs 22

of the connectors. This particular structure is better illustrated in Fig. 1. The cushioning material 25 will yield before the electrical parts when they are thus bound 5 down and prevent any injury thereto.

The connectors are preferably made relatively thin, as shown in the drawing, so as to make a snug fit with the various parts and to coöperate with them without making 10 an unsightly structure.

It will be seen that the parts will remain in position and the electric connections be maintained, even though the armature is rotated at a high velocity of speed, and even 15 though it is jarred and shaken when so rotated. The elements employed are easily and cheaply constructed and assembled, and when so constructed and assembled the resulting structure is neat in appearance as 20 well as efficient and durable.

I have shown this particular embodiment of my invention and the details employed therein for the purpose of better describing my invention and not that I wish to be 25 limited thereto, as it will be apparent to those skilled in the art that numerous and extensive departures may be made from the form and details thereof, without departing from the spirit of the invention.

30 I claim:—

1. In an armature for dynamo-electric machines, the combination of an armature shaft having a plurality of recesses therein, each of which is provided with a top opening and end walls tumbled in to restrict the 35 said top opening, linings of insulating material for said recesses, a commutator segment in each recess within said lining, each segment provided with a recess in one end and electric conductor connectors, one for 40 each commutator segment, each connector having a short limb extending under its associate commutator segment and into the recess under the end thereof, said connectors 45 being provided with relatively long limbs extending each along one of the ends of the commutator slots and insulated from the walls of said slots by an insulating lining, said long limbs being adapted to be folded 50 over along the armature shaft, armature windings connected one to each of said long limbs of said connectors and threads wound around said armature shaft over the long limbs of said connectors and the ends of

the armature windings attached thereto 55 binding the long limbs of the connectors and the ends of the armature windings attached thereto to the armature shaft.

2. In an armature for dynamo-electric machines, the combination of an armature 60 shaft provided with commutator segment slots, commutator segments in said slots, insulating material lining said slots, insulating the segments from the shaft, circuit connectors each provided with two limbs, one 65 limb of each of said connectors extending under one of said commutator segments, the other limb of each of said connectors extending along the end of its associate commutator segment and being folded over 70 along the armature shaft, armature windings, one connected to each of said connectors and means to bind the ends of said armature windings and the folded over portions of said connectors to said armature 75 shaft.

3. In an armature for dynamo-electric machines, the combination of an armature shaft, a commutator slot in said shaft, a 80 commutator segment in said slot, means for insulating the segment from the walls of the slot, a circuit connector provided with a flexible portion connected to said segment, the flexible portion being bent away from the segment along the armature shaft, an 85 armature winding connected to the flexible portion of the commutator and means to bind the flexible portion of the connector and the end of the armature winding to the 90 armature shaft.

4. In an armature for dynamo-electric machines, the combination of an armature shaft, a commutator segment connected to and insulated from said shaft, a circuit connector connected at one end to said segment 95 and folded away from said segment along said shaft, an armature winding connected to said connector and means to bind the end of the connector folded along said shaft and the end of the armature winding to the 100 armature shaft.

In witness whereof, I have hereunto signed my name this 6th day of November, 1916.

FRED N. MIZER.

Witnesses:

JOHN PEHRSSON,
L. P. VALIQUET.
